UNITED STATES PATENT OFFICE.

ANKER S. LYHNE, OF BRIDGEPORT, CONNECTICUT.

ELECTRIC LANTERN.

Application filed August 25, 1921. Serial No. 495,175.

To all whom it may concern:

Be it known that I, ANKER S. LYHNE, a citizen of the United States, residing at Bridgeport, county of Fairfield, State of Connecticut, have invented an Improvement 5 in Electric Lanterns, of which the following is a specification.

My invention relates to electric lanterns, particularly to those provided with a container for dry cells, or other source of current in which the individual cells are easily accessible for purposes of renewal. The object of my invention is to provide an improved device of the above class which shall 15 be of simple and rigid construction, easily adapted for the renewal or insertion of a dry cell and conveniently carried in the hand.

To these and other ends my invention 20 consists in certain improvements and combination of parts as will be pointed out with greater particularity in the claims appended to this specification.

Referring to the drawings—

25 Figure 1 shows a front view of my assembled lantern.

Figure 2 is a section on the line 2—2 of Figure 1.

30 Figure 3 is a rear view of the same lantern shown by Figure 1.

Figure 4 is a rear view of the front wall 17.

Figure 5 shows the switch for turning on and off the current for the lamp.

35 Figure 6 is a detail of the switch bushing with the handle shaft removed.

The numeral 10 indicates the container 40 of metal or other suitable material for housing the lamp 11 and dry cells 20, or other source of current used, and is shown in the drawing as being provided on its front face with the lamp 11 and the switch 12 located just above the lamp for the purposes of turning on and off the current. In order 45 that the container may be conveniently carried, a handle 13 is shown secured to the top thereof, while for purposes of suspending the lantern from a hook or other convenient support, a downwardly projecting tongue 50 16 is fixed to the rear face of the container 10. As shown in Figure 3 the rear wall 14 of my container may be hinged in order 55 that it may be swung open to permit the direct insertion or removal of the dry cells 20 and may be provided with a sliding bolt

15 or other convenient means for retaining the hinged wall 14 in a closed position. Immediately to the rear of the front wall 10 of the container is a plate or wall 17 preferably of insulating material provided with 60 recesses 18 and 19 through which are inserted the switch and lamp respectively. This plate or wall is removably secured in the container by any suitable means such as screws 17' passing through the front 65 wall 10'. Secured to the rear of the plate or wall 17 are a plurality of resilient holders 21 co-operating with the sides of the dry cells 20 to secure them to the wall 17. Located above and below the holders 21 are 70 the spring conductors 22 and 23 for co-operation with the bottom and top portions respectively, of the battery for closing the circuit through the lamp. In the arrangement shown in Figures 2 and 4 it will be 75 apparent that the holders 21 support the main weight of the battery, but it will nevertheless be apparent that the lower spring contacts 22 also support a portion of the weight of the battery. A conductor 24 80 is disposed so as to connect the rear of the lamp 11 with one of the conductors 22. The top conductor 23 with the same dry cell is connected through the conducting strip 25 with the lower contact 22 of the 85 other cell and the conductor 26 connects the top of this last mentioned cell through the switch with the casing and the outside of the lamp 11. From the foregoing description it will be apparent that the dry cells 90 are connected in series and the circuit is completed as follows: from the rear of the lamp through conducting tongue 24, lower contact 22, dry cell held by the holder shown on the left in Figure 4, upper left 95 spring contact 23, conducting strip 25, lower right spring connector 22, right dry cell, upper right spring connector 23, conductor 26, and switch 12 to the casing of the container, reflector 36 and outside screw 100 threads of the lamp 11. As shown in Figure 5 when the switch is open the conductor 26 is out of contact with any metal of the switch and when the latter is closed the lug 27 contacts with the conductor 26 to close 105 the circuit through the conductor and casing.

As shown in Figures 5 and 6 the details of my switch comprise a plate 28 secured to the front wall of the container. Extending 110

through the plate 28 is the switch shaft 29 provided at the rear end with the contact lugs 27 and at the front with the operating handle 30 for rotating the same. A guide bushing 31 for the switch shaft 29 is secured to the plate 28 and provided with notches 33 in the front end thereof, one side of each notch being beveled or inclined to permit the handle 30 to ride out of the notch by co-operation with the inclined side thereof. A spring 32 co-operates with the plate 28 and the shaft 29 or lug 27, tending to move the shaft rearwardly and hold the handle 30 into co-operation with the notches in the bushing 31, in order to prevent accidental movement of the switch. As the handle 30 of the switch is turned the shaft 29 is drawn forward against the action of the spring 32 until the handle is ready to engage the next notch in the bushing, so that the switch is always retained in either an open or closed circuit position.

Among the advantages of my invention may be enumerated the fact that a compact and neat container is provided for housing the lamp switch and dry cells or other source of current used which is convenient to handle as a unit, or which may be suspended from the wall by means of the depending tongue 16 secured to the rear thereof. The rear wall 14 of the container being hinged provides a convenient means of access to the interior of the container for directly inserting or removing one of the dry cells, and since the conductors 22 and 23 are secured to the same wall and are arranged to co-operate with the respective battery electrodes, no additional wires or connections are necessary and no binding posts are required. Also as the battery supports, the contacts engaging the poles of the battery, the connections between these contacts, and the connection therefrom to the switch are all mounted on the single insulated plate 17, these elements may all be assembled thereon outside of the container without interference from the walls of this container, and then the whole assembly may be quickly and easily secured in the container, greatly reducing the cost of manufacture. This assembly may with equal facility be removed for inspection and repair. With the switch disposed in the position indicated, the most convenient location is attained and there is no liability for the switch to be accidentally moved from the position intended when it is constructed in the manner described above.

I claim:

1. In an electric lantern combination with a container, of an upright supporting wall of insulating material removably secured in said container, of means on said wall for clamping a plurality of dry cells thereto, a lamp carried by said container, and a plurality of conductors fixed to said wall for

connecting said dry cells when held by said means and also connecting them with said lamp.

2. In an electric lantern combination with a container, of an upright supporting wall of insulating material removably secured in said container, of means thereon for securing thereto a plurality of dry cells, a lamp carried by said container, and resilient conductors secured to the wall for connecting said cells when held by said means, at least one of said resilient conductors arranged to help support one of said cells and form an electrical connection with said lamp.

3. In an electric lantern, the combination with a container, of a lamp carried thereby, an upright supporting wall of insulating material removably mounted in said container, resilient means for supporting a dry cell from said wall, and conductors fixed to the wall to yieldably contact with said cell and lamp and close the circuit through the lamp and dry cell.

4. In an electric lantern, the combination with a container, a supporting wall of insulating material mounted in said container, of an electric lamp carried by the container, a flexible metal holder for a dry cell fastened to the wall, yieldable conductors fixed to the wall above and below said holder, and adapted to engage the electrodes at opposite ends of said dry cell, one of said conductors having electrical connection with the lamp.

5. In an electric lantern, the combination with a container, of a wall of insulating material in said container provided with a recess therein, an electric lamp and reflector carried by the container and extending through said recess, yieldable holders attached to the wall on the inside of the container and adapted to support a plurality of dry cells, flexible conductors fixed to the wall on each side of each holder for connecting said cells in series, and a rotary snap switch located above said lamp for opening and closing the circuit through said lamp and cells.

6. In an electric lantern, the combination with a closed container, of a lamp and reflector secured to one side of said container, one of the walls of the container being adapted to open and close, a wall of insulating material within the container, means mounted on the insulating wall adapted to co-operate with the sides of a dry cell for supporting the same out of contact with the walls of the container, and resilient conductors carried by the insulating wall adapted to engage the top and bottom of said cell and said lamp whereby when said container is open a dry cell may be directly inserted and simultaneously connected with said lamp.

7. In an electric lantern the combination

with a container, of a switch having a metal supporting plate, a rotatable shaft extending therethrough, a metal bushing on the plate and around the shaft, a handle on 5 said shaft for turning the same, a yieldable conductor insulated from said container, a lug also on the shaft adapted to co-operate with said yieldable conductor, the end of said bushing adjacent the handle being provided with notches to retain the handle in a given position, one side of each notch being inclined or beveled to facilitate movement of the handle past the notch, and a spring in co-operation with said plate and lug tending to move the shaft longitudinally 15 and keep the handle engaged with its notch on the bushing to prevent accidental operation of the switch.

In testimony whereof I affix my signature.

ANKER S. LYHNE.
